UNITED STATES PATENT OFFICE.

JOHN C. KLINE, OF PITTSBURGH, PENNSYLVANIA.

DOOR LATCH-LOCK.

Specification of Letters Patent No. 12,240, dated January 16, 1855.

To all whom it may concern:

Be it known that I, JOHN C. KLINE, of Pittsburgh, in the county of Allegheny and State of Pennsylvania, have invented a new and useful Improvement in Door- Locks; and I do hereby declare that the following is a full and exact description of the construction and operation of the same, reference being had to the annexed drawings, forming 10 part of this specification, in which—

Figure 1 is a view of the lock (after removing the coverplate) when unlocked; Fig. 2 a view of the lock, when locked; Fig. 3 a section through the line I—II of Fig. 1, and 15 Fig. 4, a perspective view of the knob and shank.

In all these figures the same letters of reference indicate the same parts.

A is the case; p, its cover plate. 20 a, a' are two key holes, in reversed positions near each end of the lock; b b', screw-holes, to fasten the lock on the door.

B is the bolt.

c, c' are notches for the night key to set 25 in; d d', shoulders to stop the bolt by the key tumbler; e e, the back cross piece of the bolt, against which the arms of the knob shank operate.

C is the key tumbler.

30 f f' are notches for the bolt key to set in. g g' are projections or noses, to set against the shoulders d d' respectively, when the key tumbler is turned by the key.

h is a stationary pin, on which the key 35 tumbler turns; a screw thread is cut in the pin, in which the screw enters, which fastens the coverplate p to the case A of the lock.

D is the spring receiver (set in between 40 the noses g g') with broke corners forming oblique surfaces, against which the noses operate, when the key tumbler is turned.

E is the spring, set on a pin h fastened to the bolt.

F is the knob; G, the knob shank; l l', two 45 arms cast in one piece with the knob shank; the arms l l' are instead of a knob tumbler, which is generally cast separate and fitted to the shank; in order to enable the shank to be introduced into the lock, the arms l l' 50 are in displaced positions (as shown in Fig. 4), and a slot m cut out from the circular shank hole in the case, wide enough, to allow one of the arms l or l' to pass through.

After having described all parts of which 55 the lock consists I proceed to describe the

operation of it as follows: By turning the knob right or left, the bolt is drawn back by the action of the arm l or l', in the common way, and the spring E forces the bolt back again, when the knob is let loose. The Fig. 60 1 shows the bolt disengaged from the key tumbler, in which case the bolt can be freely worked by the knob, but by turning the bolt key n, the tumbler is brought into the position as represented in Fig. 2, in which the 65 nose g sets against the shoulder d of the bolt, and the part o of the tumbler rests against the side of the bolt; and the spring receiver D (being pushed back by the inclined, or oblique faces between g' and D) 70 rests against the nose g' of the key tumbler. In this position the bolt is prevented from being moved by the knob. The Fig. 2 shows at the same time, how the night key q sets in the notch c, whereby the bolt is stopped. 75 The shape of the key tumbler is such, that a key inserted in either of the key holes will operate it. The drawings show the lock, when used for left hand lock; the lock key is to be inserted in the key hole a, and the key 80 hole a' is used to receive the night key, which latter is to be put in from the backside of the lock, before the same is fastened to the door, its end butting against the wood work of the door, whereby it is secured in its place 85 (see Fig. 3).

To use the lock as right hand lock (in reversed position of that shown in the drawings), the night key would have to be put in the hole a, and the hole a' would be used 90 for the bolt key.

The advantage in my improved lock consists in the simplicity of the construction, by having only one bolt to do the service of latch bolt, key bolt and night bolt, when at 95 the same time, it can be used right or left, by using any of the key holes for the night key, and the other for the bolt key.

What I claim herein as new and desire to 100 secure by Letters Patent is:—

The arrangement in double keyholed right and left hand locks of the key tumbler (c) with its noses or projections (g, g') in relation to the spring receiver D and the shoulders (d, d') of the bolt, as herein set forth. 105

JOHN C. KLINE.
